UNITED STATES PATENT OFFICE.

HERMANN ERBS, OF PHILADELPHIA, PENNSYLVANIA, ASSIGNOR TO HIMSELF AND JOHN BARTH, OF SAME PLACE.

DESIGN FOR A SHAWL.

Specification forming part of Design No. 5,506, dated February 6, 1872.

Specification describing a Design for a Shawl Fabric produced or invented by HERMANN ERBS, of Philadelphia, Pennsylvania.

Design for a Shawl Fabric.

The figure in the accompanying drawing represents a portion of a shawl composed of fabric made in accordance with my design, which consists of alternate zigzag ribs *a* and narrow checkered stripes *b*. The ribs are, in the present instance, raised, and the checkered stripes depressed or flat; but this is immaterial and forms no portion of my design.

The zigzag ribs and checkered stripes are continued uninterruptedly throughout the whole of the fabric, without regard to the pattern of

the latter, the ribs and stripes being both of the same color, as shown at *c* or *d*; or of different colors, as seen at *f*; this depending upon the nature of the pattern and taste of the manufacturer.

Irrespective of the colors employed, or of the pattern of the shawl, I claim—

The design for a shawl fabric, substantially as described, and as illustrated in and by the accompanying drawing.

In testimony whereof I have signed my name to this specification in the presence of two subscribing witnesses.

Witnesses: HERMANN ERBS.
WM. A. STEEL,
HARRY SMITH.
